United States Patent Office

Des. 229,501
Patented Dec. 4, 1973

229,501

WAGON

Mario A. Pasin, Oakbrook, Ill., assignor to Radio
Steel & Mfg. Co., Chicago, Ill.

Filed Apr. 14, 1972, Ser. No. 244,320

Term of patent 14 years

Int. Cl. D21—01
U.S. Cl. D34—15 AJ

FIG. 1

FIG. 2

FIG. 3

FIG. 4

FIG. 5

FIG. 1 is a rear perspective view of a wagon showing my new design;

FIG. 2 is a top plan view thereof;

FIG. 3 is a front elevational view thereof, the roll bar having been omitted for convenience of illustration;

FIG. 4 is a left side elevational view thereof, the right side being a mirror image thereto;

FIG. 5 is a rear elevational view thereof; the steering handle having been omitted for convenience of illustration.

I claim:

The ornamental design for a wagon, as shown and described.
